H. P. HOMERS

MOP HEAD

Filed Dec. 26, 1924

Inventor
Harry P. Homers
or Seymour Farren
Attest

UNITED STATES PATENT OFFICE.

HARRY P. HOMERS, OF NEW HAVEN, CONNECTICUT.

MOP HEAD.

Application filed December 26, 1924. Serial No. 758,167.

To all whom it may concern:

Be it known that I, HARRY P. HOMERS, a citizen of the United States, residing at New Haven, in the county of New Haven and State of Connecticut, have invented a new and useful Improvement in Mop Heads; and I do hereby declare the following, when taken in connection with the accompanying drawings and the characters of reference marked thereon, to be a full, clear, and exact description of the same, and which said drawings constitute part of this application, and represent, in—

Fig. 1 a side view of a mop-head, constructed in accordance with my invention.

Fig. 2 a side view of the same.

Fig. 3 a view in vertical section.

This invention relates to improvement in mop-heads, and particularly to mop-heads which consist of two clamping-jaws, one provided with a socket for the reception of a handle, and a movable jaw adapted to be connected with the stationary jaw, so as to clamp a mop between the ends of the jaws. The object of this invention is to provide simple and convenient means for forcing the jaws together, and the invention consists in the construction as hereinafter described and particularly recited in the claims.

In carrying out my invention, I employ a fixed jaw 5, formed integral with a socket 6, into which a handle 7 is inserted. This fixed jaw includes a gripping-edge 8. Yieldingly mounted in the fixed jaw is a post 9, cut away in its upper face to form an undercut lip 10. The movable jaw 11 is provided with ears 12, which extend on opposite sides of the socket 6, to which it is secured by a rivet 13, and this jaw is formed with gripping-teeth 14 in line with the gripping-teeth 8. This jaw is also formed with a clearance-hole 15 for the passage of the post 9. Pivotaly mounted on the jaw 11 is a cam-lever 16, similar to the lever of a well-known form of sash fastener, provided with a cam-rib 17 to engage with the lip 10 of the post 9, so that, when so engaged and turned, the gripping-edges 8 and 14 will be forced together against a mop 18. Preferably, the cam-lever will be so proportioned and arranged that, when turned to the locked position, the finger-piece 19 will stand in a plane

parallel with the plane of the socket 6, as shown in Fig. 1 of the drawings.

The post 9 has a certain amount of play with relation to the jaw 5, to permit it to slightly rock, as may be necessary to compensate for the movement of the parts in adjusting the mop. The finger-piece 19 is comparatively long, so as to give proper leverage to permit the jaws to be firmly crowded together against the mop without great strain upon the fingers.

In this construction, the movable jaw is pivotally connected with the socket and, consequently, when the mop is adjusted, it cannot become detached, and by providing the post with a lifting-and-locking cam, the introduction or removal of the mop is facilitated.

I claim:

1. A mop-head, comprising a fixed jaw formed integral with a socket and provided with a gripping-edge, a movable jaw pivotally connected with said socket and formed with a gripping edge complementary to the gripping edge of the fixed jaw, a post yieldingly mounted on the fixed jaw and extending through the movable jaw, a lever pivotally mounted on the movable jaw in a plane parallel therewith and formed with a cam-rib coacting with said post for crowding the two jaws together.

2. A mop-head, comprising a fixed jaw formed integral with a socket and provided with a gripping edge, a movable jaw pivotally connected with said socket and provided with a gripping edge complementary to the edge of the fixed jaw, a post mounted in the fixed jaw and extending through the movable jaw, said post cut away on one side to form a lip, an overhanging lever pivotally mounted on the movable jaw in a plane parallel therewith and formed with a cam-rib adapted to engage with said lip, whereby the rotation of the lever will crowd the gripping edges of the jaws together.

In testimony whereof, I have signed this specification in the presence of two subscribing witnesses.

HARRY P. HOMERS.

Witnesses:

HARRIET R. VOLTZ,
IRENE HAYDEN.
